UNITED STATES PATENT OFFICE.

EDGAR A. WRIGHT, OF DAVENPORT, IOWA.

CULTIVATOR.

SPECIFICATION forming part of Letters Patent No. 242,497, dated June 7, 1881.

Application filed May 23, 1879.

To all whom it may concern:

Be it known that I, EDGAR A. WRIGHT, of Davenport, in the county of Scott, Iowa, have invented certain new and useful Improvements 5 in Cultivators, of which the following is a specification.

This invention relates to that class of machines, generally wheeled, which have vertically-swinging beams or drag-bars to carry 10 the shovels or plow-points; and the object of the invention is to render the operations of the machine easier and less laborious to the attendants by applying springs thereto in such manner that they will assist the operator in 15 raising the beams and shovels attached thereto from their operative to their inoperative positions, and this without having the springs exert any objectionable lifting strain upon the beams when the latter are in action.

20 To this end the invention consists in applying lifting-springs in such manner that they exert upon the beams a maximum power or strain when the latter are above an operative position.

25 The spring, operating in accordance with my improved plan, may be made and applied in various forms, which will readily suggest themselves to the skilled mechanic without departing from the limits of my invention.

30 My springs may be arranged to sustain the whole or any desired portion of the weight of the beams when the latter are raised, and they may be arranged to exert a slight lifting strain when the beams are in action, or, if preferred, 35 arranged to cease their lifting strain entirely at such time.

The essential feature of my invention consists in applying a lifting spring or springs in such manner that they do not increase their 40 lifting strain as the beam is depressed, the construction preferred being such that the springs exert an increased lifting action as the beams rise from an operative to an inoperative position.

45 I am aware that springs have been applied in various ways to assist in lifting the beams in this class of machines; but in all cases their arrangement was such that they acted with an increased lifting strain as the beams were 50 lowered, the consequence of which arrangement was, that the springs exerted their greatest upward strain when the shovels were in the

ground, at a time when it was desirable that the shovels should not be lifted, and on the other hand exerted but little force when the beams 55 were elevated, and when it was required that they should be sustained to relieve the operator. This old action, it will be seen, is the reverse of that which is desired, and the principal object of my invention is to reverse the 60 old mode of action and have the springs act with little or no upward strain when the shovels are in the ground, but with a strong upward pressure when the beams are lifted.

The accompanying drawings illustrate one 65 manner of embodying my invention. The springs represented in the drawings are adapted to serve the double purpose of holding the beams down, and of lifting them, or assisting to lift them, when they are raised above an 70 operative position. No claim is made in the present case to this duplex action of the springs, nor to the peculiar form or arrangement of the springs, otherwise than as regards the feature of exerting an increasing or a maximum strain 75 on the beams as the latter rise, the peculiar construction of the spring being already covered in a patent hitherto granted to me.

Figure 1 is a perspective view of a cultivator provided with my improved spring, the beams 80 being shown in the operative position; Fig. 2, a vertical section through one side of the same, showing one of the beams partly raised and the spring acting to assist in its elevation; Fig. 3, a similar section, showing a modified arrangement, the spring being attached to the frame instead of the beam, as in the preceding figures; Fig. 4, a vertical section, showing the same construction as Fig. 2, but with the beam raised and sustained by the spring; Fig. 5, a 90 view showing the modified arrangement represented in Fig. 3 with the beam elevated and sustained by the spring.

The machine may be of any suitable character as regards its general construction, that 95 shown in the drawings being the usual and well-known form of the ordinary double-shovel wheeled cultivator, consisting, mainly, of an arched axle, K, sustained at its ends by wheels B, and connected, by the couplings g, to the 100 beams of two plows, h, the couplings being of such construction that the beams are free to swing both vertically and laterally.

Referring to Figs. 1 and 4, it will be seen

that each beam has secured to its top, at some distance from its couplings g , one end of a spring, C , the opposite end of which latter bears against the under side of a pulley or 5 roller, a , attached to the axle directly over the coupling which connects the beams with the latter. This spring is curved, as shown at d in the drawings, and has near one end a bend or angle, d' . When the beams are lowered so 10 that the shovels enter the ground, the outer end, d' , of the spring outside of the bend or angle acts beneath the roller, as shown in Fig. 1, and the springs consequently tend to urge and hold the beams and their shovels down 15 in their operative position; but as the beam rises above an operative position the end of the spring moves forward beneath the roller until the angle d' passes the same, whereupon the spring instantly changes its action, and 20 the portion d tends to raise the beams, thus enabling the attendant to lift them easily above an operative position with the shovels clear of the ground, as is required in turning the machine or carrying the same to or from the field. 25 It will be noticed on referring to Figs. 2 and 4 that as the beam is elevated the fixed end of the spring approaches the roller, and consequently as the operative portion of the spring is lessened in length the spring acts with increased force and effect as the beam ascends. 30 Of course the force of the spring is lessened by its loss of tension as it swings upward with the beam; but this loss is more than compensated for by the shortening of the active portion of the spring and its increased leverage as the bearing of the roller approaches its rear or fixed end, and hence it is that the lifting force or effect of the spring increases during the rise of the beam. 35 The parts should be so proportioned, if it is designed that the spring shall hold the beam down, that the angle d' will pass the roller and change the action of the spring at or about the instant that the shovels leave the ground. It 40 is manifest, however, that the shoulder d' and the portion d may be omitted and the spring continued directly outward past the roller, in which case the spring will exert a lifting action upon the beams when the shovels are in 45 the ground; but by properly proportioning the parts the lifting action may be so greatly reduced when the shovels are in the ground that it will not materially affect their operation, and will not cause them to ride from the ground 50 improperly.

By giving the spring the proper length and strength, and properly arranging the parts in relation to each other, the spring may be caused to act with a greatly-increased effect as the 55 beam is elevated; or it may be caused to act with substantially uniform effect, so as to balance, or substantially balance, the weight of the beam and shovels, in which case, however, the machine would require greater attention 60 on the part of the operator to prevent the shovels from riding out of the ground. 65

The spring shown in the drawings is made of spring steel wire, with its lower end coiled and secured to the beam by means of an adjustable clamp, s . The roller is mounted on a journal secured to the axle by means of a vertically-adjustable clamp. By adjusting the clamps which hold the spring and roller, the force with which the spring acts and the variation in its strain may be modified as desired. 70 The location of the roller may be changed; but it is preferred to attach it directly above the coupling, as shown, for the reason that the lateral movement of the beam will then have no effect upon the action of the spring. 75

In Figs. 3 and 5 the arrangement shown is simply the reverse of that above described, the spring being secured to the axle and the roller attached to the beam. The general form of the spring, with its bend or angle, and its 80 double action upon the beam, are the same as in the arrangement above described.

It will be noticed, on reference to Figs. 3 and 5, that in the arrangement therein represented, as in the first-described arrangement, 90 the roller or point of bearing approaches the fixed end or fulcrum of the spring as the beam rises, so that the spring acts with increasing power, and also with increasing effect, in elevating the beam. 95

In this second arrangement the bend or shoulder of the spring to hold the beam down may be used or not, as preferred.

While it is believed that the form of spring represented in the drawings is preferable to 100 all others, the invention includes, as before stated, any spring so combined with the beam or its equivalent that a greater or stronger lifting force or effect is exerted upon the beam when the latter is above the operative position 105 than when it is in use; or, in other words, the invention includes any and all beam-lifting springs the effect of which is lessened or avoided when the beam descends to an operative position. 110

I believe myself to be first to apply a spring in such manner as to secure the above mode of action, and the first to so apply a spring in such manner that as it loses tension it acts with an increasing force or effect to lift the 115 beam, or, in other words, with an effect which is not lessened by the decrease in the tension of the spring within the usual limits of operation.

Among other arrangements which may be 120 substituted for that shown is that of having a radius bar or link introduced between the spring and beam as a substitute for the curved spring and roller.

While the invention is designed more particularly for use in connection with wheeled cultivators, it is obvious that it may be applied to various other machines containing substantially the same requirements. 125

By arranging the lifting-springs to act with 130 a minimum effect when the beams are down, or to cease their effect at such time, as de-

scribed, I am enabled to secure the perfect action of the spring and to avoid the tendency of the shovels to rise from the ground when the machine is in action, at the same time relieving the attendant of the whole, or nearly the whole, labor of lifting the beams out of action.

Having thus described my invention, what I claim is—

- 10 1. In a cultivator, the combination of a vertically-swinging drag bar or beam and a lifting-spring which acts with increasing force or effect on the beam as the latter rises, and vice versa.
- 15 2. In a wheeled cultivator, the combination of a vertically-moving beam and a lifting-spring, substantially as described, whereby an increasing upward strain is communicated to the beam as the latter rises.
- 20 3. The combination of a wheeled frame, a vertically-moving beam or drag-bar attached

thereto, and a lifting-spring, substantially as described, which exerts a greater strain or effect upon the beam when the latter is elevated than when it is depressed.

25 4. The combination of a vertically-moving beam, a lifting-spring, and a shifting or changing bearing or fulcrum, whereby the lifting action or effect of the spring upon the beam is increased as the beam is elevated, substantially as described and shown.

30 5. A vertically-movable beam, in combination with a lifting-spring, connected therewith by a changeable or shifting bearing, substantially as described, whereby the lifting force 35 or effect of the spring upon the rising beam is maintained, notwithstanding the decreasing tension of the spring.
